UNITED STATES PATENT OFFICE.

JOSEPH G. SAVAGE, OF BROOKLYN, ASSIGNOR TO PATTERSON & GREENOUGH,
OF NEW YORK, N. Y.

DESIGN FOR A SHAWL.

SPECIFICATION forming part of Design No. 13,472, dated December 5, 1882.

Application filed July 14, 1882. Term of patent 14 years.

To all whom it may concern:

Be it known that I, Jos. G. SAVAGE, of Brooklyn, Kings county, New York, have invented a new and original Design for Shawls, of which the following, in connection with the annexed drawings, is a full, clear, and exact description.

The figure in the annexed drawing presents a surface or plan view of a shawl embodying my design.

As may be noted, my design applies more especially to a square shawl or a double square shawl; but the external outline of the shawl may vary somewhat from a square without departing from the characteristic effect of my design.

The main feature of my design may be stated to consist in a division of the figured surface of the shawl by lines across the center at right angles into four squares or corner-sections differently figured, so that when the shawl is folded on either of its diagonals, as indicated by the dotted lines in the drawing, it will present a differently-figured square or corner-section to form the back or center of the shawl when worn on the person, according to which diagonal the shawl may be folded on and which side is turned outward, as will be readily understood. Thus, referring to the drawing, it will be noted that division-lines cross the center of the shawl at right angles, thereby dividing the field of the shawl into four square corner-sections, *a b c d*, the upper corner-square, *a*, being plain or having a plain center, the lower corner, *b*, being checked or plaid, while the two remaining corners are striped, as illustrated. Hence, if the shawl is folded on the horizontal diagonal *x x* with the lower half outward, the shawl will present a plaid back or center when worn on the person, while half of the striped corners *c* will fall over the arms of the wearer. If with the same fold the opposite side is turned outward, the shawl will then present a plain back or center, while the stripes will fall over the arms as before. If the shawl is folded on the opposite diagonal *y y*, a striped back or center will be presented when thrown over the wearer. Hence by this design a number of varying and agreeable effects or appearances may be obtained with

the same shawl, thus greatly enhancing the dressy value of its figuring, and enabling the wearer to obtain a number of distinct agreeable changes of appearance with the same article of dress, which gives the shawl a very ornate and dressy quality and renders it a very desirable article of apparel.

The principle of this design or the manner of disposing the figuring on the field of the shawl, as set forth, as may be noted, is not confined to the specific character of the figures which may be introduced into each of the four corner squares or sections, for the figuring of each square might vary considerably from that shown without departing from the principle of the design. I do not, however, here claim this generic feature of the design, having reserved this for the subject of a future application; but I here show a special arrangement of figuring on this principle which is simple and advantageous, and to which I restrict my present application—that is, the figured effect is produced by a series of stripes, *ff*, which extend along two sides of the shawl at right angles, and are continued from the margins to or about the center of the shawl, which stripes intersect over one-quarter the area of the shawl, thereby forming one plaid or check corner-square, while the remaining area consists of two striped corner-squares at right angles to the plaid square and a plain corner-square diagonally opposite to the plaid square. A few border-stripes, *gg*, are run along the two sides of the shawl at right angles to the stripes *ff*, in order to furnish the striped and plain squares with a border of about the ordinary character; but these border-stripes are not an essential feature in my design. The stripes, as shown, are of a prismatic or shaded character; but I neither claim this particular form of stripe as new nor confine my design to it, as will be understood.

I do not here claim the generic feature of the design herein set forth, consisting in a division of the area of the shawl across the center at right angles into four square corner-sections differently figured, whereby the shawl may be folded on either diagonal, and thereby present a differently-figured square or corner-section to form the back or center of the shawl; but I

here restrict myself to the specific features of the design herein illustrated, as expressed in the following clauses.

What I claim is—

- 5 1. The design for a shawl, consisting in a division of its area by lines across the center at right angles into four square or similar corner-sections, one square having a plain center, another being checked or plaid, and another 10 striped, substantially as herein set forth.
2. The design for a shawl, consisting in a division of its figured surface across the center into four squares or corner-sections parallel with the sides, one of said squares having a plain ground or center, the diagonally-opposite square having a plaid ground, and the two 15

squares at right angles thereto being striped, substantially as herein set forth.

3. The design for a shawl, consisting in a series of stripes running at right angles to each other along two sides of the shawl, and extending from the margins thereof to or about the center, leaving one square corner of the shawl plain, rendering the diagonally-opposite corner plaid by the intersection of the said stripes, while the two remaining corners are striped, substantially as herein set forth.

JOSEPH G. SAVAGE.
